[57]

ABSTRACT

This disclosure is directed to an improved method of construction of drumhead type cartons (i.e., parallelepiped cartons whose ends are sealed by independent, taut membranes) in which a fillet means of hot melt material having a generally right triangular cross section is deposited along that portion of the manufacturer's joint which extends into the carton dust flaps to provide an uninterrupted peripheral surface to which the membrane may be tightly adhered. Absolute tightness at the joint is enhanced by simultaneously cross-crushing and cross-sealing the membrane, fillet, and underlying flap portions by a specially configured sealing platen.

DRUMHEAD FOR END SEALED CARTONS AND
METHOD OF MAKING THE SAME

BACKGROUND OF THE INVENTION

Many airtight, siftproof, and moistureproof paperboard carton constructions for liquid and pulverulent materials are formed from parallelepiped cartons and have their opposite ends sealed by "safety shield" members or "drumhead" membranes adhered to the carton end flaps and side flaps (dust flaps). Presently, in commercially useful drumhead cartons, the membrane material and/or the inner surfaces of the flaps to which the membranes are adhered are thermoplastic. For example, a resin, wax or other material which may be easily heat sealed may be coated on the membrane or flaps. The strength of these drumhead cartons is often custom tailored to meet packaging requirements by the choice of laminated materials used to construct the blanks. Moreover, with the development of improved coated and laminated paperboard materials and improved thermoplastic films, the tightness and imperviousness of membrane sealed cartons of the aforementioned type have been greatly improved, and these cartons have continued to find ever increasing acceptance and widespread use in diverse packaging applications.

It is to a further improvement in the airtightness or sift-proofness of the attachment of the drumhead to the end carton flaps that the present invention is directed. More specifically, where the carton to be sealed includes a manufacturer's joint extending into its dust flaps, it is often possible for the applied membrane to stretch over the right angular step defined by the edge of the manufacturer's joint in an end flap during membrane attachment (indeed, the likelihood of such an occurrence is increased as a function of the increase in caliper of the carton blank). The stretching of the membrane over the step forms a small gap or channel and prevents an end sealed carton from being hermetically or otherwise completely tightly sealed. A proposed solution to this problem has been to form the channel and thereafter (after membrane attachment) to score the membrane and end flap transversely of the manufacturer's joint in order to eliminate the channel at the site of the line score. While the score did not eliminate the channel, it sought to cut off communication between the inside of the carton and the carton exterior through the portions of the channel which remained. It is to this specific problem area of drumhead carton formation that the present invention is directed.

SUMMARY OF THE INVENTION

In the present invention, an uninterrupted and continuous bonding surface for the membrane is provided at the carton end flaps, that is, all bonding surfaces are free of steps. Of course, there are no problems in adhering the drumhead membrane to those carton flaps which are comprised of a single planar surface, those flaps which are not compound flaps. Rather, the problem is introduced in a compound flap, i.e., the flap containing the manufacturer's joint where there is a compound surface made up of an underlying flap and overlying glue segment.

More specifically and in accordance with the principles of the present invention, a fillet having a sloped surface is formed in situ at the right angular step defined by the edge of the manufacturer's joint. This fillet completely fills the step and is in the form of a thermoplastic material, such as a hot melt material commonly employed in packaging applications. Thereafter, the step is eliminated completely by cross-crushing (cross scoring) during heat sealing.

As will be appreciated, a membrane placed over the open flaps of a carton end may be effectively heat sealed along the entire extent of each of the flaps, since the surfaces thereof are all smooth, flat, and uninterrupted by any sharp or abrupt drops, such as would be present absent the fillet and cross-crushed portions at the edge of the manufacturer's joint. In this manner, it is now possible to effect highly efficient, leak-proof, hermetic seals in drumhead cartons.

For a better understanding of the present invention and its attendant advantages, reference should be made to the following detailed description taken in conjunction with the accompanying drawings.

5

DESCRIPTION OF DRAWINGS

FIG. 1 is a perspective view of one end of a drumhead carton just prior to sealing of the membrane to the carton end flaps.

10 FIG. 2 is a fragmentary, cross-sectional view of the drumhead taken along line 2-2 of FIG. 1.

15 FIG. 3 is a perspective view schematically showing cartons being advanced along a horizontal path by a packaging machine and being glued, taped, and sealed during such advance.

20 FIG. 4 is a perspective view of one end of the carton after the latter has been taped and completely sealed.

25 FIG. 5 is an enlarged fragmentary cross-section taken substantially along the line 5-5 of FIG. 4.

30 FIG. 6 is a fragmentary perspective view of the underside of a sealing shoe for sealing the cartons shown in FIG. 3.

DESCRIPTION OF THE PREFERRED EMBODIMENT

Referring now to FIG. 1, a typical drumhead carton 10 (of which only one end is shown, it being understood that the opposite end is a mirror image of the illustrated end) includes a first side wall 11, a rear wall 12, a second side wall 13, a front wall 14, and a glue flap 15, consecutively articulated along parallel vertical creases 16. The glue flap 15 extends for the entire depth of the carton and above the upper carton edge 17 as a glue flap segment 18. Front and rear carton closing flaps 19 and 20 are articulated to the front and rear walls at the carton edges 17, as shown, and dust flaps 21 and 22 are similarly articulated to the carton side walls at the end edges 17 thereof. As shown, the manufacturer's joint 30 is formed by adhering the glue flap 15 to the first side wall 11 and by adhering the glue flap segment 18 to the dust flap 21. As will be appreciated, the glue flap segment 18 and the dust flap 21 together form a compound dust flap 31 having a generally angular step 32 (see FIG. 2) therein defined by the end edge 33 of the glue flap segment 18 and the surface 34 of the dust flap 21.

45 In accordance with the invention, the right angular step 32 is eliminated and a bridge is formed between the upper surface 35 of the glue flap segment 18 and the upper surface 34 of the dust flap 21 by a solid fillet of thermoplastic material 36, as shown in FIGS. 1 and 2. More specifically, the fillet 36 initially has a generally right angular cross section, the hypotenuse of which extends between the upper surfaces of the glue flap segment 18 and dust flap 21, as best shown in FIG. 2. In accordance with the principles of the invention, it is this material to which an overlying sealing membrane 42 may be heat sealed during drumhead formation. It will be appreciated that absent the fillet 36, it would be extremely difficult, if not impossible using conventional platen sealing techniques, to seal the membrane along the edges of the step, more specifically, along the vertical surfaces 33 of the glue flap segment 18.

50 In accordance with the principles of the invention, the fillet 36 is formed in situ, advantageously during the carton erection and filling operations and after the carton tube has been squared into a parallelepiped configuration and its end flaps are dust flaps outfolded into the position shown in FIG. 1. At this stage in carton manufacture, a daub of molten or at least spreadable hot melt material is placed at the vertical edge 33 of the glue flap segment 18, and it is then spread along the step to form the fillet 36, which fillet may extend from the carton edge 17 outward beyond the area of drumhead attachment. In the illustrated embodiment, the fillet is extended from the carton edge 17 to the end of the compound glue flap 31, however, it is only necessary for the fillet to intersect the area 40 of peripheral bonding of the membrane 42 to the outfolded flaps. 55 More specifically, and as shown in FIG. 3, after being squared

75

and placed on the carrier of the packaging machine, cartons 10 are advanced continuously along a horizontal path into engagement with a switch A. Actuation of switch A energizes a solenoid B which fires an air cylinder C, which, in turn, momentarily opens a valve D to apply a quantity of hot melt 36 on the trailing dust flap 21 through a nozzle E.

With continued advance of the cartons, the sealing membrane 42 is applied and then is sealed, in tape form, to a group of cartons simultaneously by a group of heated sealing shoes F which move along the path with the cartons and which are lowered into pressured engagement with the outfolded flaps and upper ends of the cartons 10. An exemplary sealing mechanism is disclosed in more detail in Lense U.S. application Ser. No. 835,008, filed June 20, 1969 and titled "Packaging Machine With Continuous Motion Sealer."

As shown in FIG. 6, the lower or sealing surfaces of each sealing shoe F are especially contoured and define the circumscribing sealing zones 40. A relieved area G of the shoe receives and presses against the glue flap segment 18 overlying the dust flap 21, while the other embossing-sealing surfaces H of the shoe tend to press against the exposed surfaces of the dust flap 21, and the flaps 19, 20, 22. As an important aspect of the invention, a so-called peninsula or finger I (FIG. 6) extends into the relieved area G and serves to cross-crush and to cross-score the glue flap portions 18', the dust flap portions 21', and the hot melt 36 at the step between the flaps 18 and 21 so as to form a dam 44 extending transversely of the dust flap and across the joint (see FIGS. 4 and 5). Importantly, and as shown in FIG. 5, the hot melt at the dam 44 is flattened by the finger I, thus changing the shape of the fillet of hot melt at the area of the dam and allowing the membrane 42 to be sealed to both the glue flap 18 and the dust flap 21 in a common horizontal plane 41 defined by the surface of the platen finger I. Advantageously, the membrane 41 is secured to exposed portions of the single thickness flaps 19, 20, 21, 22 by embossed areas H of the sealing platen to form embossed-sealed surfaces 46, while the membrane is secured to the composite flap by unembossed portions I and G of the platen to form smooth-sealed surfaces 45 (FIG. 5). As will be understood, this construction creates a barrier to leakage along the manufacturer's joint and forms a new and improved drumhead seal which is superior to those heretofore obtainable.

The four corners of the carton are, of course, included within the sealing zones 40. Extra tightness of the seal of the membrane to the corners may be effected by expanding the corner areas 43 or surfaces by crushing, controllably tearing, or otherwise re-forming the same. After the membrane is heat sealed to the flaps, the carton flaps 19-21 are infolded, as shown in FIG. 6, to complete the carton.

It should be understood that the specific drumhead closure and the method of effecting the same herein illustrated and described are intended to be representative only, as certain changes may be made therein without departing from the clear teachings of the disclosure. Accordingly, reference

should be made to the following appended claims in determining the full scope of the invention.

I claim:

5. In a parallelepiped carton having consecutively articulated first side, front, second side, and rear walls with said rear wall adhered to said first side wall by a glue flap articulated to said rear wall; said carton having first, front, second, and rear closing flaps articulated to each of said first side, front, second side, and rear walls, respectively, and a glue flap segment articulated to said glue flap; said glue flap segment being adhered to said first flap and defining therewith a composite flap having a discrete step therein, an improved drumhead closure comprising:
  15. a thermoplastic fillet means disposed in and along said step;
  - b. said fillet means providing a bridging surface between the upper surface of said glue flap segment and the upper surface of said first flap;
  - c. a heat sealable membrane tightly adhered about the periphery of the end of said carton at the edges thereof to said glue flap segment, said fillet means, the exposed portion of said first flap not underlying the glue flap segment, said front flap, said second flap, and said rear flap;
  - d. said membrane being adhered by straight line heat seals;
  - e. a portion of said upper surface of said glue flap segment being crushed into the plane of the upper surface of said first flap along one of said heat seals
  - f. whereby the end of said parallelepiped carton is sealed in an airtight and siftproof fashion.
20. The carton of claim 1, in which
  - a. said discrete step is generally right angular;
  - b. said fillet has a generally rectangular cross section in the region of hat sealing of the membrane to the glue flap and first flap.
25. The carton of claim 1, in which
  - a. said fillet extends substantially the entire length of said composite flap.
30. A method of applying a drumhead membrane to the outfolded four flaps of carton, one of which flaps is a composite flap having a glue flap segment overlying an underlying flap portion and defining therewith a discrete step, said method comprising the steps of:
  - a. depositing a molten thermoplastic fillet means in and along said step;
  - b. covering the outfolded four flaps with a heat sealable membrane,
  - c. applying heat and sealing pressure to said membrane and flaps along discrete linear zones;
  - d. simultaneously crushing a portion of said glue flap into the plane of said underlying flap portion and flattening said fillet means in said zone at said step.
35. The method of claim 4, in which steps (a) through (d) are effected during advance of the carton along a predetermined path by a packaging machine.
